A. J. SPILLANE

SICK ROOM OUTFIT

Filed Feb. 14, 1927

UNITED STATES PATENT OFFICE.

ARTHUR J. SPILLANE, OF TOLEDO, OHIO.

SICK-ROOM OUTFIT.

Application filed February 14, 1927. Serial No. 168,018.

This invention relates to sick-room outfits for persons of certain religious beliefs and creeds, such as Roman Catholics, and objects of the invention are to provide a device of this character which is compact, and when not in use may serve as a useful ornament, and consists in the features of construction and arrangement hereinafter described.

10 The invention is shown by way of illustration in the accompanying drawings, in which:

Fig. 1 is a front elevation of the sick-room outfit; Fig. 2 is an enlarged plan view of 15 the box with the cover removed; Fig. 3 is a transverse section on the line 3—3 of Fig. 2; Fig. 4 is a fragmentary view of the back of the outfit showing the manner in which the tray is mounted.

20 The illustrated embodiment of the invention comprises a box 1 of cruciform shape, and is preferably constructed of aluminum or other light, non-breakable material. Formed in the walls of the box 1 are shoulders 2 against which rests the cover 3 of the box. The cover 3 may likewise be of aluminum, and is shaped similarly to the box.

Attached to the cover 3 is an effigy 4, in 25 this instance the figure of the crucified Christ. It will be apparent that when there is need for a sick-room outfit and when the cross is required by a person, the cover 3 of the box may be removed and handed to the 30 sick person, and as this may be hung on a wall or in any other convenient place, upon arrival of the priest to administer the last sacrament all the necessary utensils required by him are immediately at hand.

35 For enhancing the ornamental appearance of the outfit and to provide a tray which is handy for emergency purposes and for use in connection with the administration of the last sacrament, a tray 5 is detachably supported on the back of the box 1 by hooks 6. The face of the tray 5 may be provided with 40 radial grooves 7, or may be inclined outwardly to simulate an halo for the image or effigy of Christ mounted on the front of the box. The tray may have a polished surface 45 so as to reflect the light shining thereon and result in a most pleasing and attractive appearance.

The utensils required in administering the

last sacrament are ordinarily, the blessed 55 candles, the holy water, a small piece of cotton, a small spoon and a strip of linen.

These articles are compactly arranged within the box 1, and as shown, candles 8 and 9 are arranged within arms of the box 60 with a roll of fabric cloth 9^a in between the candles, and a spoon 10 on top of the cloth 9^a. A small receptacle 11 having a cork 12 for containing holy water is arranged in another arm of the cross, while a tube 12^a 65 for containing cotton with which the sick person is anointed may be kept.

For holding the candles, bottle and tube in place and to close the outer ends of the box, caps 13 are provided with flanges 14 70 for fitting over the ends of the box and overlapping the cover 3 and retain the latter in place. These caps are formed with recesses 15 frictionally to engage the articles above mentioned. An outstanding advantage of 75 the caps 13 resides in the fact that upon being disengaged from the box they may serve as supports or mountings for the articles above enumerated. Thus by removing the caps 13 to which the candles are attached, 80 the candles are, at the same time, removed from the box, and in this manner the caps serve as standards for the candles so that 85 they will maintain an upright position and may be quickly placed in position of use.

While I have shown and described a construction which is the best form known to me at the present time, numerous changes in details of construction and arrangement may be effected without departing from the 90 spirit of the invention, especially as defined in the appended claim.

What I claim as new and desire to secure by Letters Patent is:

A sick room outfit comprising a box of 95 cruciform shape having an internal ledge, said box having open ends, a cover of crucifix shape having an effigy to be positioned on the outside of the box and adapted to rest on said ledge, caps fitting over the ends of 100 said box and overlapping the cover for retaining the latter in place, and means on said caps for holding articles to be positioned inside the box.

In testimony whereof I have hereunto 105 signed my name to this specification.

ARTHUR J. SPILLANE.
